UNITED STATES PATENT OFFICE.

ROY O. DARTT, OF MONTELLO, WISCONSIN.

ANGLE-GAGE FOR DRILLS.

1,207,717.

Specification of Letters Patent. Patented Dec. 12, 1916.

Application filed April 25, 1916. Serial No. 93,423.

To all whom it may concern:

Be it known that I, Roy O. DARTT, a citizen of the United States, and resident of Montello, in the county of Marquette and 5 State of Wisconsin, have invented certain new and useful Improvements in Angle-Gages for Drills, of which the following is a specification.

The present invention relates to new and 10 useful improvements in boring and drilling devices and has particular reference to supporting, gaging, and angle regulating devices for drill bits.

The primary object of my invention is to 15 provide a bit-holding and gaging device whereby the angle and depth of a hole may be regulated by controlling the drill bit.

Another object of my invention is to provide a device of the character described 20 which may be readily applied in position on the work to be drilled, and also to provide a device of the above character which is simple in construction, cheap to manufacture, strong and durable, and effective in 25 operation.

Other objects and advantages to be derived from the use of my improved doweling gage for drill bits will appear from the detailed description, and the claims, taken with 30 an inspection of the accompanying drawings, in which:

Figure 1 is a top plan view of a gage embodying the improvements of my invention, Fig. 2 is an end elevational view of the same, 35 Fig. 3 is a front elevational view of my improved gage, and Fig. 4 is an enlarged perspective view of the gage proper showing the same detached from operative position.

Referring more particularly to the drawings, wherein similar characters of reference 40 designate like and corresponding parts throughout the various views, 1 and 2 designate the base portion of my improved gage, the inner ends of the said portions 1 and 2 being extended upwardly to provide supporting walls 3 and 4 connected by means 45 of an adjustable plate member 5 having right angularly formed portions 6 and 7, pivotally engaged with the walls 3 and 4, respectively, by means of bolts 8 having wingnuts 9 on their extremities.

The use of my invention, which will more 50 clearly appear hereinafter, necessitates in some instances the securement of the device to the work. For this purpose I provide work engaging members 10 and 11 having

down-turned end portions 12 and 13, respectively. The down-turned portions are provided with oppositely directed retaining screws 14 and 15 for gripping engagement 60 with the work. The base portion 2 is in the present instance the larger of the said base portions, and, of course, the section 11 is the larger, the said work engaging section being of a size coincidental with the size of 65 the base portion 2. To adjust the work-engaging element, three screws are provided, two in one of the down-turned portions 13 thereof, and one in the other portion.

The drill receiving and guiding device of 70 my invention embodies preferably a disk-like supporting body 15 mounted on the plate member 5 by means of a bolt 16 secured against movement by wingnut 17. The work-engaging members are secured to the 75 base members 1 and 2 by means of a plurality of bolts 14' and 15' having wingnuts thereon. The bit carrying members comprise an arm 18 extending transversely from the disk-like body 15 and having a curved 80 outer end 19. The tubular portion 20 is receivable in the curved portion 19 and carries the bit 21, said bit being of any of the usual forms. Of course, it will be understood that the arm 18 and the body 15 are 85 integrally carried as best shown in Fig. 4. A clamping rod 22 having the U-shaped end 23 engaging the tube 20 is carried by a second lateral extension 24, the free end of the said U-shaped portion 23 extending 90 through the outer end of the arm 18 and having a wingnut 25 mounted thereon for tightening the U-shaped portion in engagement with said tube. It is to be understood that the bit 21 must snugly fit within the 95 tube in order to be effectively guided in operation.

The free end of the extension 24 is provided with an internally threaded enlargement 26 for reception of a screw 27 having a head 28 relatively large in circumference formed on the upper end thereof. A block 29 carried by a U-shaped bolt 30 embracing the upper end of the bit 21 and rotatable therewith serves to engage said head 28 to 100 limit the depth to which the bit is driven.

It is of course, to be understood that various sized tubular members 20 may be employed for different sizes of bits, and it will 105 also be readily understood that for different lengths of bits the screw 27 may be removed and a longer screw placed in its position. A

projection 31 carried by the disk-like member 15 is adapted to move across a graduated scale 32 formed on the plate 5 to indicate the angle at which the hole is being bored. 5 The walls 3 and 4 are likewise provided with extensions 33 moving across graduated scales 34 carried by the laterally bent portions 6 and 7, of the member 5.

Thus it will be seen that the angular 10 position of the bit forwardly, rearwardly, and laterally may be determined previous to boring a hole. It will also be apparent that on removing the work-engaging members 10 and 11 the user may place the device 15 upon a plain surface, such as a table and retain the gage in position by kneeling thereon.

From the above description taken in connection with the accompanying drawings, it 20 is thought that a clear and comprehensive understanding of the construction, operation and advantages of my invention may be had, and while I have shown and described my invention as embodying a specific structure, I desire that it be understood that I 25 may make such changes in said structure as do not depart from the spirit and scope of the invention as claimed.

What I claim as new and desire to secure 30 by Letters-Patent is:

1. A drill guiding device of the class described, including base members, work-engaging elements associated therewith, a drill carrying frame, said drill carrying frame being angularly adjustable relative 35 said work engaging elements, a drill carrying member carried by said frame, said member being angularly adjustable on said frame, means for said members to accommodate 40 date drills of various sizes, and depth regulating means for the drill.

2. In a drill guide of the class described, work-engaging elements, a drill supporting frame associated therewith, and means carried by said frame for adjusting a drill for 45

wardly and rearwardly for changing the angle of the drill.

3. A device of the character described, including base members, work-engaging elements associated therewith, a carrying frame angularly adjustable between said base members, a drill carrying member adjustable on said frame whereby to forwardly and rearwardly and laterally adjust the 50 drill.

4. A device of the class described, including base members, work-engaging elements associated therewith, an adjustable carrying frame associated with said base members, a drill carrying member associated with said frame, means for removably mounting a drill thereon, a regulating screw, and means carried by the drill for engagement with said screw whereby to regulate the depth to 60 which the drill operates.

5. A drill gaging device of the character described, including base members, work-engaging elements removably associated therewith, a carrying frame adjustable angularly on said base members, a drill carrying member angularly adjustable on said frame having indicating means associated therewith, and depth regulating means for the drill.

6. The combination with a drill guiding 75 device including base members, an adjustable carrying frame associated with said base members, a drill carrying member comprising a disk, a regulating screw member, a bit carrying member, arms extending laterally from said disk providing retaining means for the regulating screw and said bit carrying member, and a block carried by the drill for engagement with said screw whereby to regulate the depth to which the drill 80 85 operates.

In testimony whereof, I affix my signature hereto.

ROY O. DARTT.
